DENTAL FLOSS HOLDER

Marius J. Morin, 4610 Sepulveda Blvd.,
Torrance, Calif. 90505

Filed Dec. 17, 1974, Ser. No. 533,790

Term of patent 14 years

Int. Cl. D24—99

U.S. Cl. D24—1 D

FIG. 1 is a top perspective view of a dental floss holder showing my new design;

FIG. 2 is a bottom perspective view thereof;

FIG. 3 is a side elevation view thereof, the opposite side being identical;

FIG. 4 is a bottom plan view thereof;

FIG. 5 is a top plan view thereof; and

FIG. 6 is an end elevation view thereof.

I claim:

The ornamental design for a dental floss holder, substantially as shown and described.
